UNITED STATES PATENT OFFICE.

LOUIS K. JOHNSON AND A. AUGUSTUS LOW, OF BROOKLYN, ASSIGNORS TO
THE ALDEN TYPE MACHINE COMPANY, OF NEW YORK, N. Y.

TYPE-DISTRIBUTING APPARATUS.

SPECIFICATION forming part of Letters Patent No. 337,407, dated March 9, 1886.

Application filed March 6, 1885. Serial No. 157,862. (No model.)

To all whom it may concern:

Be it known that we, LOUIS K. JOHNSON and A. AUGUSTUS LOW, citizens of the United States, residing in the city of Brooklyn, county 5 of Kings, and State of New York, have invented certain new and useful Improvements in Type-Distributing Apparatus, of which the following is a specification.

Our improvements relate to the distribution 10 by hand of types into suitable type-containing channels, in which the types are arranged in a prescribed position, one against the other, in lines or columns which are adapted for use in the type-setting apparatus.

15 The main feature of our present invention consists in the combination, with such containing-channel, of a combined type-receiving and forwarding device, into or upon the upper part of which the types may be dropped, and 20 by which they will be conducted into the containing-channels, and subsequently forwarded therein by motion imparted by hand or treadle to the said combined receiving and forwarding device.

25 Heretofore somewhat similar receivers or conduits have been used in connection with type containing or transfer channels; but in such cases they have been stationary with relation to the containing-channels, and an in- 30

dependently-vibrating pusher or forwarding device has been necessary to forward the types in the containing-channels. We dispense entirely with this independently-vibrating pusher or forwarding device by making the 35 receivers themselves capable of forwarding the type in their respective containing-channels. This we accomplish by pivoting or otherwise securing each or a series of the receivers in such manner that their lower ends may be

40 made to advance into the containing-channels, and thereby forward the types when the upper or receiving ends of the receivers are depressed by hand or treadle. As this depression may be effected while depositing the types 45 into the said upper extremities of the receivers with little additional labor and without loss of time, the use of auxiliary power for this purpose is dispensed with entirely. The receivers are arranged to return automatic- 50

ally to their normal position when released from the pressure of the hand or treadle by

means of either counterpoise-weights or retractile springs.

Our invention also includes the use of a swinging or yielding guard near the upper 5 end of the receiver, which, while it does not positively prevent the passage of type if the latter is resting upon its edge instead of upon its flat side, still has a tendency to gently turn such type over upon its flat side while passing 60 thereunder.

In the accompanying drawings our improvements are represented as applied only to a single type-containing channel, it being understood that any desired number may be combined and used in conjunction, since the construction in such case would be substantially the same.

In the drawings, Figure 1 is a top view of one of our combined receivers and forwarders 70 attached to one end of a type-containing channel; Fig. 2, a central vertical longitudinal section; Fig. 3, a front view, and Fig. 4 a rear view, of the same; Figs. 5 and 6, respective side and end views of a detachable fulcrum 75 plate or coupling between the receiver and the type-containing channel. Fig. 7 is an elevation of one extremity of the type-containing channel.

The type-containing channel A is of the ordinary construction shown in our previous applications. It may be permanently provided with the type receiver and forwarder B, if desired, in which case its side walls will be extended sufficiently at one end to afford bearings for the fulcrum b; but we prefer to make the combined receiver and forwarder B detachable, and to this end we form the type-channel A with the lateral perforations a. These perforations a correspond to and may 85 be used for the same purpose as those described in our application No. 144,776, while at the same time they afford a convenient means of securing the coupling-plate C to the end of the type-containing channel A. This coupling-plate C may be varied considerably in form, its office being simply to connect the two devices together in proper relation to each other. As shown in the drawings, it is provided with a downwardly-projecting tongue, c, which enters the channel A, and which is perforated to 95 correspond to the perforations a in the side 100

walls of the type-containing channels, so that a pin or key, d , may be used to hold the parts together. It is also formed with shoulders $c' c'$, which rest upon the upper edges of the 5 type-channel walls, and with projecting lugs $c^2 c^2$, to which the under side of the receiver B is secured by the pivot b . The receiver B is in the form of the ordinary type-conduit, b' , provided at its upper end with an enlarged 10 but converging receiving-surface, b^2 . The side walls of the receiver may be made to terminate and merge into this receiving-surface b^2 in such manner as to leave its extreme upper portion free and unobstructed, for the greater 15 convenience of the operator while depressing that end of the device with his fingers. The side walls of the receiver B terminate at its lower end at the point of juncture with the side walls of the containing-channels when the 20 receiver is in its normal position. In such position its floor is inclined at a suitable angle to insure the descent of the types. The lower extremity, b^3 , of its floor also projects some distance into the type-channel A, and is preferably curved convexly, so as to guard the 25 types gradually and gently into position therein. The type-containing channel is also preferably inclined sufficiently to cause each type, when deposited therein, to lean against the 30 next preceding type. When the upper end, b^2 , of the receiver B is depressed, its curved lower extremity, b^3 , is thrown forward in the type-containing channel, as indicated by dotted lines, Fig. 2, thus forwarding the whole column of type within the channel a distance 35 equal to the thickness of the number of type that may have occupied the extent of motion or stroke of the said lower end of the receiver. When the pressure upon the upper end, b^2 , of 40 the receiver is withdrawn, the device is returned to its former position by a retractile spring, e , or a counter-weight, f' , one or both of which may be used for this purpose, if desired. As shown in the drawings, the counter-weight f' is attached to the under side of 45 the curved lower extremity, b^3 , of the receiver B. When thus again in its normal position, it will be observed that a space is left in the containing-channel between the last type and 50 the curved end b^3 of the receiver sufficient to accommodate several types before it will be again necessary to depress the upper end of the receiver in order to forward them. Owing to the relative angles and inclinations of 55 the containing-channels A and the receiver-conduit b' , and to the convex curvature of the lower extremity or "pusher" portion, b^3 , of the receiver, these types as they descend one after the other arrange themselves naturally 60 in an upright position one against another; or, if one should fall back against the end b^3 of the receiver, the convex curvature of said end b^3 prevents the exposure of its face to the heel of the next descending type, which latter, by 65 striking against its side, will raise it against the end of the column, and be in turn thus raised, and so on until the space is filled.

It is not designed to make the stroke of the lower end, b^3 , of the receiver greater than that which will be equal to the thickness of a comparatively few types, say five or six; otherwise the first types descending after the retractile movement of the pusher might become deranged before reaching the rear of the column. It will thus be seen that the necessity 70 for depressing the receiver every time a type is deposited is obviated; and where several receivers are united together in a series, as hereinafter set forth, the distributor is enabled, upon an average, to dispose of a considerable number of types before repeating the operation of forwarding the types, since in ordinary composition even the most frequently used letters are interspersed with a much larger number of letters of other denominations. Where a series of receivers are thus arranged, as above indicated, so as to move together, they may be attached to a common plate, pivotally supported in substantially the same manner as the single receiver shown, 80 and having their respective receiving-surfaces b^2 arranged upon different levels, substantially as in the case of the stationary receivers shown and described in our applications Nos. 78,535, 131,261, and 146,776. Under these 85 circumstances the coupling-plate C will be in the form of a continuous plate provided with a suitable number of the downwardly-projecting tongues c , and all the channels will be secured by a simple bolt or key, d , of suitable length. A single rod, b , of proper length will also answer as a common fulcrum to all the receivers B included in the series. 90

Each receiver B is provided over the lower part of its receiving-surface b^2 with a loosely-hinged guard, G, under which all the types have to pass in order to enter the conduit b' . This guard, while it yields before a type that may be resting upon one of its edges, tends to trip such type over upon its broad or flat side, 100 when, if it is of the right thickness, it will be in position to pass under the positive gage H, situated near the lower extremity of the conduit b' ; but should the hinged guard G fail to trip such irregularly-situated type, or should 105 a type of greater thickness than that of the proper denomination have been inadvertently dropped into the receiver, the said positive guard H will prevent its descent into the containing-channel, and it will be held opposite 110 the depressions or recesses $h h$ in the side walls of the conduit b' , which recesses h afford convenient access to the fingers of the operator 115 to either turn the type upon its side or remove it, as the case may be. By arranging the hinged guard diagonally across the receiving-surface, as shown, its tendency to turn misplaced types is greatly enhanced. 120

The type-containing channels A are formed with nicks in one of their edges to designate 130 the font of type for which they are adapted, Fig. 7, for instance, indicating the number 31.

The advantages of a type-distributing apparatus in which the use of all auxiliary power

is dispensed with are of especial importance when the apparatus is used in connection with our improved type-setting apparatus described in Patents Nos. 254,019 and 271,711.

5 Since the setting and distributing apparatus are necessarily related and connected in practical use, our system of setting and distributing is thus adapted to the requirements of small printing establishments, where no 10 power is available, as well as to those of the larger establishments. The whole operation of distribution is also more completely within the supervision and control of the operator than where a constantly-vibrating forwarding- 15 pusher is employed, since he can more readily detect and rectify defects or mistakes.

If preferred, the receivers, when combined in series upon a common plate or support, may be made to vibrate for the purpose of forward- 20 ing the types by means of a treadle and connecting-rod, or in any other well-known manner.

What we claim as our invention, and desire to secure by Letters Patent, is—

25 1. In combination with a type-containing channel substantially such as designated, a vibrating type-receiver adapted to conduct types into the said channel and pivotally sup-

ported with relation thereto in such manner that its vibrations will forward the types, substantially in the manner and for the purpose described. 30

2. In combination with a type-containing channel and a type-receiving conduit capable of vibration for the purpose and substantially 35 in the manner described, a coupling-plate constructed substantially in the manner and for the purpose described.

3. In combination with a type-containing channel and a type-receiving conduit capable 40 of vibration for the purpose and substantially in the manner described, a retractile device for returning the receiving-conduit to its normal position, substantially in the manner and for the purpose described. 45

4. In a type-receiving conduit substantially such as designated, a hinged guard or type- turning device, arranged and operating substantially in the manner and for the purpose described.

LOUIS K. JOHNSON.
A. AUGUSTUS LOW.
